UNITED STATES PATENT OFFICE.

THEODORE H. NELSON, OF CHICAGO, ILLINOIS.

BURGLAR-ALARM.

1,098,362.

Specification of Letters Patent.

Patented May 26, 1914.

Application filed July 15, 1912. Serial No. 709,352.

To all whom it may concern:

Be it known that I, THEODORE H. NELSON, a citizen of the United States, residing at Chicago, in the county of Cook and State 5 of Illinois, have invented a certain new and useful Improvement in Burglar-Alarms, of which the following is a full, clear, concise, and exact description, reference being had to the accompanying drawings, forming a 10 part of this specification.

My invention relates to burglar alarms and contemplates the provision of an extremely simple and efficient device which may be secured to a window or door and 15 which will automatically close an electrical circuit if anyone should open the window or door with which it is associated or tamper with the device in any way. The various parts of the device mentioned are so constructed and arranged that the electrical contacts thereof are located near the bottom of the hollow casing forming part of the device, where they can not be reached without closing the electrical circuit.

25 Another feature of the device referred to is the fact that if the device is tampered with even to the extent of removing the screws by means of which one of the two castings forming a part of the device is secured, the electrical alarm circuit is closed.

Other advantages of the burglar alarm of my invention will appear as this description progresses.

My invention will be more clearly understood by reference to the accompanying drawings, in which—

Figure 1 is a view showing the circuit closing device in side elevation, the window frame with which it is associated being 40 shown in section; Fig. 2 is a view showing the circuit closing device in longitudinal section; Fig. 3 is an end view of the device, part of the hollow casing or socket being broken away to reveal the contact devices 45 within; Fig. 4 shows a modified form of circuit closing device embodying my invention; Fig. 5 is a cross-sectional view thereof taken on the line 5—5 of Fig. 4; Fig. 6 is a longitudinal section of a door and frame provided with a modified form of circuit closing device; Fig. 7 is a representation of an 50 electrical circuit arrangement particularly adapted for use with the circuit closing devices before mentioned; and Figs. 8 and 9 show in front and side elevation respec-

tively, the plug carrying member of my circuit closing device adjustably mounted upon the window sash with which it is associated.

Similar reference characters refer to similar parts throughout the several views.

Referring to Figs. 1 to 3 inclusive, a window sash is shown at 8 and a window frame at 9. The window frame 9 is mortised as indicated at 10. Secured to the window frame and having a hollow portion extending into an opening 10 in the window frame is the hollow casing 11. This casing is provided with a flange 12 which is held rigidly against the window frame by means of a plurality of screws 13, 13. The casing 11 is provided with a hollow head or socket 14 which is disposed at right angles to the remainder of the casing. The end of the casing 11 within the opening 10 is closed by means of suitable insulating material 14a. Extending through the insulation 14a are the spring contacts 15 and 16 and a spring 17 provided with an up-turned portion 18. The contact springs 15 and 16 constitute 75 part of an electrical alarm circuit.

Secured to the window sash by means of screws 19, 19 is the casting 20 provided with a plug 21. The plug 21 is provided at its lower end with suitable insulation 22. When the window is in its closed position, the plug 21 extends down through the hollow head or socket 14 of the casing 11 and separates the contact springs 15 and 16, which are normally in engagement with each other. When the plug 21 is in the position shown in the drawings, the spring 17 is depressed as shown. If the window sash 8 is raised the plug 21 is also raised, whereupon spring contacts 15 and 16 engage each other and the electrical alarm circuit including said contacts is closed. If the screws 19, 19 should be removed the plug 21 is raised by spring 17, allowing the spring contacts 15 and 16 to close the alarm circuit.

In the modified form of burglar alarm 100 circuit closing device shown in Figs. 4 and 5, contact spring 23 is secured to the casing 25 and contact spring 24 is insulated therefrom by suitable insulation 26. The contacts 23 and 24 which are normally in engagement with each other, are separated by means of the plug 27 carried by the casting 28. When the plug 27 is in the position shown in Fig. 4, it depresses the spring 24 out of engagement with spring 23. The 105 110

spring 24 performs the same function as spring 17 of the device shown in Figs. 1 to 3 inclusive, that is, it serves to raise the plug 27 if the screws securing the casting 28 to 5 the window sash are removed.

In the form of circuit closing device shown in Fig. 6, the member 28* carrying the plug 27* is secured to a door or swinging window as shown. The member 25* within which 10 are located suitable contact springs is secured to the door or window frame. When the door or window indicated at 29 is open, the plug 27* is withdrawn from the member 25*, thereby allowing the contact springs 15 within the member 25* to close an electrical alarm circuit.

In the circuit diagram shown in Fig. 7, a source of current is illustrated at 31, a circuit closing device at 32, a switch at 33, a 20 gong at 34, and a relay at 35. If the window or door with which the circuit closing device 32 is associated is opened or tampered with in such a manner as to allow the contact springs 32* and 32* to engage each other, 25 and the switch 33 is in the position shown, current will flow as follows: from the source of current through conductor 36, circuit closing device 32, conductor 37, switch blade 38, conductor 39, the conductor 40, gong 34, conductor 41, switch blade 42, and through conductor 43 back to the source of current. This is the simple alarm circuit. If the 30 springs of the circuit closing device should be separated, the sounding of the gong would cease.

If the switch 33 be placed so that blade 42 is in electrical engagement with conductor 44, a system is had in which the gong will be actuated when the contact springs 40 of the circuit closing device 32 are allowed to engage each other and will continue to sound even if the contact springs be separated again. If the switch be in the position referred to and the contact springs 32* and 32* are in engagement with each other, current will flow from the source of current through conductor 36, circuit closing device 32, conductor 37, switch blade 38, conductor 45, relay 35, conductor 46, switch 50 blade 42, and conductor 43 back to the source of current. When current flows through relay 35 it will attract its armature 47, thereby releasing drop 48, whereupon current will flow from the source of current through conductor 49, drop 48, conductor 50, gong 34, conductor 40, switch blade 51, conductor 52, back to the source of current. It will thus be seen that after the drop 48 is released, current will continue to flow through the 60 gong 34 to actuate the same even though the current springs 32* and 32* of the circuit closing device are separated.

Referring to the arrangement shown in Figs. 8 and 9, a portion of a window sash is shown at 53 to which there is secured by

means of a plurality of screws 55 a bracket 54. This bracket is provided with a slot 56 therein. The plug carrying casting 57 is provided with a T-shaped shank 58. This T-shaped shank is adapted to prevent the 70 casting 57 from being removed from the bracket 54 when the casting is in the position shown. The casting 57 may be secured at any position relatively to the bracket 54, by means of a thumb-screw 58* co-operating 75 with a nut 59. It will be seen that when this arrangement is used, the window sash may be opened a trifle if desired and the plug carrying member adjusted so that the alarm devices will not be actuated when the window 80 sash is in said position. The alarm devices will, however, be actuated if the window be opened any farther.

The arrangements shown in Figs. 1 to 5 inclusive are applicable to either the upper 85 or lower sashes of a window. The bracket and plug shown in Figs. 8 and 9 are primarily intended for use in connection with a lower window sash.

While I have illustrated my invention in 90 the particular embodiments herein shown and described, I do not wish to be limited to these constructions, but desire to claim broadly any equivalent constructions which may suggest themselves to those skilled in 95 the art.

What I claim is:

1. In combination with a window comprising a frame and a sash movable therein, a hollow member carried by the frame and 100 projecting therefrom into the angle between the frame and the sash, a second member carried by the sash and projecting therefrom into the angle between the sash and the frame, each of said members comprising an 105 offset portion, said offset portions being adapted to engage each other when the sash is at a predetermined position, contacts within the hollow member, and a pin carried by the second member adapted to project into the offset portion of the hollow member to operate said contacts.

2. A circuit controlling device for a burglar alarm system comprising a tubular member adapted to be carried by a window 115 frame and project therefrom horizontally into the angle between the frame and a window sash movable within the frame, said member being provided at its free end with a hollow upturned portion, a second member carried by the window sash projecting therefrom and having a downturned portion substantially in alignment with the upturned portion of the first member, contacts in said tubular member, and a pin carried 120 by the downturned portion of the second member adapted to project into the upturned portion of the first member to operate said contacts, said members when the pin is disposed in the hollow member con- 125 130

stituting a continuous connection between the frame and the sash which can not be broken without actuating the alarm devices.

3. A circuit controlling device for a burglar alarm system comprising a first member adapted to be supported by a window frame and project therefrom into the angle between the frame and a sash movable within the frame, a second member adapted to be carried by the sash and project therefrom into the angle between the sash and frame, each of said members comprising two portions disposed substantially at right angles to each other, contacts within the first member, and a pin carried by the second member adapted to project into the first member and operate said contacts, said members when said pin is disposed in the first member constituting a continuous connection between the frame and sash which can not be broken without actuating the alarm devices.

4. A circuit controlling device for a burglar alarm system comprising a first member adapted to be supported by a window frame and project therefrom into the angle between the frame and a sash movable within the frame, a second member adapted to be carried by the sash and project therefrom into the angle between the sash and frame, contacts within the first member, and a pin carried by the second member adapted to project into the first member and operate said contacts, said members when said pin is disposed in the first member constituting a continuous connection between the frame and sash which cannot be broken without actuating the alarm devices.

5. A burglar alarm system comprising a hollow member secured to a window frame, contacts within said hollow member adapted when operated, to establish a "set" condition of an alarm circuit, a bracket carried by the movable element of the window, said bracket comprising two spaced bars, a plug

carrying member mounted on said bracket, 45 said plug carrying member comprising a substantially T-shaped tongue arranged to pass between said spaced bars, a bolt and nut arranged to retain said plug carrying member at any desired point on said bracket 50 and a plug carried by said plug carrying member adapted to project into said hollow member to operate the contacts therein.

6. A burglar alarm system comprising a pair of contacts supported by a window frame, said contacts when operated adapted to establish a "set" condition of an alarm circuit, a contact operating member adapted to be supported by a movable element of the window, a supporting bracket arranged to 55 be carried by the movable element of the window, and devices for securing said contact operating member at any one of a number of points on said bracket, whereby the burglar alarm system may be placed in 60 "set" condition with the movable element of the window at any one of a number of open positions.

7. A burglar alarm system comprising a pair of contacts supported by a window frame, said contacts, when operated adapted to establish a "set" condition of an alarm circuit, a contact operating member adapted to be supported by a movable element of the window, and devices for securing said 70 contact operating member at any one of a number of positions relative to the movable element of the window, whereby the burglar alarm system may be placed in "set" condition with the movable element of the window at any one of a number of open positions.

In witness whereof, I hereunto subscribe my name this 8th day of July, A. D., 1912.

THEODORE H. NELSON.
